UNITED STATES PATENT OFFICE.

JOHN DEAM KNEEDLER, OF SIOUX CITY, IOWA.

ROAD-BED EQUIPMENT.

No. 855,643.

Specification of Letters Patent.

Patented June 4, 1907.

Application filed February 21, 1907. Serial No. 358,586.

To all whom it may concern:

Be it known that I, JOHN DEAM KNEEDLER, a citizen of the United States, residing at Sioux City, in the county of Woodbury and State of Iowa, have invented certain new and useful Improvements in Road-Bed Equipment; and I do hereby declare the following to be a full, clear, and exact description of the invention, such as will enable others skilled in the art to which it appertains to make and use the same.

My invention relates to new and useful improvements in road-bed equipment and is designed as an improvement over a former patent filed by me under date of August 20, 1906, and allowed Nov. 13, 1906.

My object is to provide a suitable cushioning plate for the rail whereby the jar coincident to the stroke of the driving wheels of the engine will be compensated for by the cushioning plate and eliminate the jar from the tie.

A further object is to provide means for readily securing the several parts of the equipment together after the bed blocks have been placed in position.

Other objects and advantages will be hereinafter referred to and more particularly pointed out in the claims.

In the accompanying drawings which are made a part of this application, Figure 1 is a top plan view of a section of a track showing my improved road-bed equipment in position thereunder. Fig. 2 is a detail sectional view on an enlarged scale as seen on line 2—2 Fig. 1. Fig. 3 is a sectional view as seen on line 3—3 Fig. 1. Fig. 4 is a bottom plan view of one of the rails showing my improved equipment secured thereto. Fig. 5 is a top plan view of one of the rail chairs. Fig. 6 is a perspective view of a locking device for securing the rails in position on the chair, and, Fig. 7 is a view, partly in section, showing the manner of applying the rail chair and cushion plates to the common form of wooden tie.

Referring to the drawings in which similar reference numerals designate corresponding parts throughout the several views, 1 indicates a bed block which is preferably pro-

vided with extensions 2 and 3, the extensions 2 being designed to extend below the rails 4 while the extensions 3 are made longer than the extensions 2 and are adapted to receive and form a support for a metallic tie 5, said tie being employed to secure the bed-blocks

ment and spaced a predetermined distance apart. The body of the bed-block 1 is provided at its central portion with a cavity 6 in which is seated a rail chair 7.

Each corner of the rail chair 7 is provided with a post 8 which posts 8 form channels for the reception of the tie 5 and the base of the rails 4, the tie 5 being seated directly on the floor of the chairs 7, said posts being reinforced by means of flanges 9 which are located in the channel formed to receive the base of the rail.

It is my desire to form the bed blocks of any suitable form of plastic material and in order to prevent the same from becoming disintegrated from the jar caused by the contact of the wheels with the rails I dispose in the bottom of the cavity 6 and immediately below the rail chair 7 a cushion plate 10 upon which said rail chair rests and I also dispose between the base of the rails and the metallic tie 5, an auxiliary cushion plate 11, said cushion plates being preferably formed of Babbitt metal, or like soft metals so that the same will have a yielding tendency.

In equipping railways with block systems it is the common practice to use one rail of the trackway to convey electric currents and it is my object to form the cushion plates of nonconducting material so that the upper cushion plate will insulate the track rail from the tie 5 so that the electric current will not pass through the metal tie and into the opposite rail.

The auxiliary plate 11 is so arranged that it will support the base of the rails 4 slightly above the surface of the bed-block and extensions 2 so that when the wheels of the train engage the rails the jar caused by the stroke of the wheels will be received by the cushion plates, when by the time the rail engages the surface of the bed block and extensions 2 the weight of the train, only, will be directed thereon which is a very important item as it has been found in practice that a constant jar directly upon the bed blocks coincident to trains passing thereover soon causes the bed blocks to crumble and be destroyed.

The bottom of the bed block and the extensions thereon are provided with longitudinally extending grooves 12 and 13, the walls of which diverge so that the earth upon which the bed blocks rest will thoroughly pack in the grooves and prevent casual displacement of the bed blocks.

Extending longitudinally in the groove 13 is a locking plate 14 which is provided with laterally extending ears 15 and by placing the locking plate within the mold before the bed block is cast, the ears 15 will be embedded within the adjacent walls of the groove 13 and hold the locking plate firmly in position.

In order to securely lock the several parts of the road bed equipment to the bed block I provide securing bolts 16 which are provided at their lower ends with elongated heads 17 which engage the lower face of the locking plate while the upper ends 18 of the securing bolts are preferably formed angular and disposed one upon each side of the base of the rail and extend a sufficient distance above the same to receive clamps 19, one edge of which is cut away to fit the contour of the rail base and is clamped thereon by means of wedges or the like 20, said wedges extending through ways 21 in the upper ends of the bolts, the openings 19^a in the clamps 19 being angular to receive the angular ends of the bolts 16 so that said bolts will be held against rotation when secured in the clamps.

In order to insert the bolts 16 into engagement with the locking plates 14 after the bed blocks have been placed in position I provide slots 22 through the central portion of the bed blocks, said slots being of sufficient width to receive the elongated heads 17 while the plate 14 is likewise provided with openings 23 which register with the slots 22 so that when the heads 17 are properly placed within the upper end of the slots 22 they may be directed entirely through the bed blocks and plates 14 and in order to hold the bolts rigid with the locking plates, I provide lugs 24 upon the bolts 16 and in line with the elongated heads 17, so that as soon as the heads 17 are projected through the openings 23 the bolts 16 may be partially rotated which will result in extending the lugs 24 and heads 17 at right angles to the longitudinal plane of the openings 23 and engage the adjacent portions of the locking plate between the lugs and head.

While I have shown the openings in the rail chair and parts carried thereby as snugly fitting the upper ends of the bolts 16 it will be understood that said openings may be constructed of the same size as the slots 22 so that the bolts may be directed through the several parts after the same have been assembled upon the bed blocks.

In Fig. 7 of the drawing I have shown my preferred manner of securing my improved form of rail chair and cushion plate to the usual form of wooden tie and in this instance the bed block is dispensed with and the rail chair placed directly upon the tie, after which spikes or the like 25 may be directed through the openings in the rail chair and into the tie thus securing the rail in position upon the chair.

In order to prolong the life of the bed blocks I prefer to round the several corners thereon so that when encountered by any solid object they will not become readily chipped and broken as would be the case if said corners were left square or pointed.

By this construction it will be seen that I have provided means for cushioning the jar caused by a train traveling over the rails and by elevating the base of the rail slightly above the surface of the bed block and disposing the same upon cushion plates the noise of the train will be materially lessened and the abrupt jar entirely removed from the bed blocks, and by using nonconducting material to form the cushion plates, an electric current may be passed through one rail and prevented from passing to the opposite rail through the metallic tie.

It will further be seen that I have provided means for preventing movement of the several parts of the road bed equipment after the same have been secured to the bed blocks.

What I claim is:

1. In a road bed equipment, the combination with bed blocks having a cavity in the central portion thereof and grooves in the lower faces thereof; of a rail chair seated in said cavity, a cushion plate below said chair, posts at each corner of said rail chair forming channels, a tie disposed over said rail chair and between said posts, an auxiliary cushion plate above said tie, a locking plate in one of said grooves, bolts extending through said bed blocks and secured to the locking plate and means at the upper end of said bolts to secure a rail to the bed blocks and on said auxiliary cushion plate.

2. In a device of the class described the combination with a bed block having extensions thereon, a cavity in the upper face of said bed block, intersecting grooves in the lower face thereof and vertically disposed slots through said bed block; of a rail chair adapted to be seated in said cavity, posts at each corner of said chair to form channels on the chair, a rail seated in one of said channels, clamps between said posts adapted to engage the base of the rail, cushioning means for said rail and chair, a locking plate in one of said grooves and partly embedded in the block, said plate having openings therein adapted to register with the slots in the bed block and a bolt removably secured to said plate and extending through the chair and clamps and means to secure the clamps on the bolts whereby the rail will be held in position on the bed block.

3. In a device of the class described the combination with a bed block having vertically disposed slots therethrough; of a rail, a chair for said rail, clamps adapted to engage the base of said rail, a locking plate on the lower face of said bed block and partly embedded therein, said plate having open-

ings registering with the slots in the bed block, bolts extending through said slots and openings in the rail chair and clamps, an angular head on the lower end of said bolts 5 adapted to engage the lower face of the locking plate, lugs on said bolts adapted to engage the upper face of said locking plate and prevent longitudinal movement of the bolt and means to secure the clamps on the upper 10 ends of the bolts and the base of the rail.

4. In a device of the class described the combination with a bed block; of means to secure a rail thereto comprising a locking plate having openings therein, bolts adapted 15 to be disposed through slots in the bed block and openings in the locking plate, an angular

head on the lower ends of said bolts adapted to engage the lower face of the locking plate, lugs on said bolts adapted to engage the upper face of said locking plate whereby said 20 bolts will be normally fixed to the plate; clamps disposed over the upper ends of said bolts and onto the base of the rail and means to secure said clamps in position.

In testimony whereof I have signed my 25 name to this specification in the presence of two subscribing witnesses.

JOHN DEAM KNEEDLER.
